UNITED STATES PATENT OFFICE.

HARRY A. OKEL, OF WHEELING, WEST VIRGINIA.

ANIMATED-FIGURE SCORING GAME.

Application filed September 3, 1926. Serial No. 133,443.

The invention primarily has for its object to provide a combined toy and game in which is provided an acrobatic figure and means for delivering a projectile to contact 5 with the said figure to cause it to perform amusing antics.

The invention further has for its object to provide a device of the character stated in which the projectile is directed by the 10 acrobatic figure while performing its antics into association with counting or scoring means.

With the above and other objects in view that will hereinafter appear, the invention 15 still further resides in the novel details of construction, combination and arrangement of parts, all of which will be first fully described, then be particularly pointed out in the appended claims, reference being had to 20 the accompanying drawing, in which:—

Figure 1 is a perspective view illustrating the invention.

Figure 2 is a detail rear elevation illustrating the projectile impelling gun.

In the drawing in which like numerals of reference indicate like parts in all the figures, 1 represents the base of the device which is provided with a flat top formed 25 on an incline, the said incline being directed downwardly rearwardly toward the rear end of the device as is clearly shown in Figure 1 of the drawing and for a purpose 30 later to be described.

The inclined top plane 2 of the base delivers 35 toward a plurality of score recording stalls 3 having value or score indicating indicia marked thereon as indicated in Figure 1.

A cylindrical projectile impelling gun 5 is provided and is mounted upon the base 40 rearwardly of the stalls 3 in vertical position with its open discharging end directed upwardly. The gun includes an impelling plunger 6 between which and a suitable stop 45 mounted in the lower part of the gun is interposed an impelling spring 7.

A trigger 8 is secured to the plunger and projects radially from one edge thereof through the vertical slot 9 provided in the 50 wall of the gun 5. The upper end of the slot 9 forms a limiting stop 10 and the lower end of the said slot is turned horizontally in the manner illustrated to form a keeper shoulder 11.

Thus when it is desired to load the gun 55 the operator grasps the trigger and forces

the trigger downwardly and secures the same under the keeper shoulder 11, thus holding the plunger at its lowermost position with a maximum of energy stored up 60 in the impelling spring 7. When the trigger is released from the shoulder by a slight touch sufficient to rotate the same beyond the keeper shoulder into the main slot 9 the tension of the spring will be released and 65 the plunger forced upwardly until stopped by engagement of the trigger with the limiting stop 10 and any projectile loaded into the gun above the plunger is forcibly thrown out of the discharge end of the gun. 70

The discharge end of the gun delivers into the receiving end of an arcuate projectile or ball guide 12, the discharge end 13 of the said guide being directed downwardly in a manner illustrated in Figure 1 of the drawing. 75 The guide 12 is supported and secured in the position described and illustrated by suitable uprights 14.

A toy figure 15 is provided and is equipped with a pair of forwardly out-stretched arms 16, a bucket basket or other suitable projectile receiving member 17 being held in the hands 18 with which the arms 16 are provided. 80

The arms 16 of the figure are pivoted as 85 at 19 to the uprights which support the discharge end of the guide 12, the said pivot being so positioned that the figure is held in vertical planes in the manner illustrated in Figure 1 of the drawing with the receptacle 17 in position for receiving the projectile or ball discharged from the discharge end of the guide 12. 90

In operation, a projectile 20 (preferably a ball as indicated in dotted lines in Figure 1) 95 is inserted into the gun and, after it has been cocked by lowering the plunger and securing the trigger beneath the shoulder 11, the trigger is released from the keeper shoulder 11 and the projectile impelled out of the 100 gun into the arcuate guide 12.

As the projectile leaves the discharge end 13 of the guide it is directed into the receptacle 17 carried in the out-stretched arms of the toy figure and by its weight and the 105 force of its impact the toy figure is caused to spin upon its pivotal mounting. As the figure makes its first turn and as the receptacle 17 is traveling upwardly just after passing the lowermost point of its travel the projectile is thrown out of the said receptacle 110 onto the inclined top plane 2 of the base 1.

Due to the force with which the projectile is thrown out of the receptacle and owing to the incline of the said top plane of the base the projectile is delivered into one or another 5 of the plurality of scoring stalls 3.

In the structure described I not only provide a mechanical toy which affords great amusement by reason of the antics performed by the acrobatic figure under influence of the projectile being directed into the receptacle carried by the said figure, but additional amusement is also provided by the 10 scoring values and the invention thus constitutes not only an amusing toy but also a 15 scoring game.

From the foregoing description, taken in connection with the accompanying drawing it is thought that the novel details of construction, the manner of use and the advantages 20 of my improved toy game will be readily understood by those familiar with such devices.

What I claim is:

1. A device of the class described comprising 25 a projectile, an acrobatic figure, means for rotatably mounting the figure, an impelling gun, and an upwardly and downwardly arched trackway for guiding the projectile impelled from the gun into contact 30 with the figure to cause it to rotate about a horizontal axis.

2. A device of the class described comprising 35 a projectile, an acrobatic figure, means for rotatably mounting the figure, an impelling gun, an upwardly and downwardly arched trackway for guiding the projectile impelled from the gun into contact with the figure to cause it to rotate about a horizontal axis, and scoring devices into association 40 with which the projectile is directed by the figure while rotating.

3. A device of the class described comprising 45 a base, uprights on the base, an arcuate guide trackway carried by the uprights and having an entrant end and a delivery end, an acrobatic figure rotatably carried by certain of the uprights beneath the delivery end of the guide trackway, a projectile, and an impelling gun for impelling the projectile 50 into and through the guide trackway to cause it to strike the acrobatic figure and impart rotation thereto.

4. A device of the class described comprising 55 a base, uprights on the base, an arcuate guide trackway carried by the uprights and having an entrant end and a delivery end, an acrobatic figure rotatably carried by certain of the uprights beneath the delivery end of the guide trackway, a projectile, and an impelling gun for impelling the projectile 60 into and through the guide trackway, said acrobatic figure having outstretched arms provided at their ends with a receptacle into which the projectile is adapted to pass on leaving the delivery end of the guide 65 trackway and by its weight impart rotation to said acrobatic figure, and scoring stalls on said base into which the projectile is adapted to be thrown as the acrobatic figure rotates. 70

5. A device of the class described comprising 75 a base, uprights on the base, an arcuate guide trackway carried by the uprights and having an entrant end and a delivery end, an acrobatic figure rotatably carried by certain of the uprights beneath the delivery end of the guide trackway, a projectile, and an impelling gun for impelling the projectile 80 into and through the guide trackway, said acrobatic figure having outstretched arms provided at their ends with a receptacle into which the projectile is adapted to pass on leaving the delivery end of the guide trackway and by its weight impart rotation to said acrobatic figure, and scoring 85 stalls on said base into which the projectile is adapted to be thrown as the acrobatic figure rotates, and said base having its top face inclined downwardly from a point beneath the acrobatic figure to the position of 90 said scoring stalls.

6. A device of the class described comprising 95 a projectile, an acrobatic figure, means for rotatably mounting the figure, an impelling gun, and an upwardly and downwardly arched trackway for guiding the projectile impelled from the gun into contact with the figure to cause it to rotate about a horizontal axis, said figure having means to receive the projectile and retain the same during part 100 of its rotation, and scoring stalls into which the projectile is adapted to be directed by the figure for the purposes specified.

HARRY ALFRED OKEL.
